Des. 210,721
Patented Apr. 9, 1968

210,721

AUTOMATED UNIT FOR ANALYZING CHEMICAL SAMPLES

Leonard N. Albrecht, Mill Valley, Calif., assignor to Warner-Lambert Pharmaceutical Company, Morris Plains, N.J., a corporation of Delaware

Continuation-in-part of design application Ser. No. 4,002, Sept. 23, 1966. This application Oct. 4, 1967, Ser. No. 8,855

Term of patent 14 years

(Cl. D16—2)

110 a 3

110 a 2

FIG. 1 is a front perspective view showing my new design.

FIG. 2 is a left side elevational view showing my new design.

FIG. 3 is a right side elevational view showing my new design, and

FIG. 4 is a back view.

This application is a continuation-in-part of my co-pending design application Ser. No. D. 4,002 filed Sept. 23, 1966 and now abandoned.

I claim:

The ornamental design for an automated unit for analyzing chemical samples, as shown and described.
